UNITED STATES PATENT OFFICE.

HEINRICH TRAUN, OF HAMBURG, GERMANY.

COMB.

SPECIFICATION forming part of Letters Patent No. 740,338, dated September 29, 1903.

Application filed September 6, 1902. Serial No. 122,291. (No model.)

To all whom it may concern:

Be it known that I, HEINRICH TRAUN, a citizen of Germany, residing at Hamburg, Germany, have invented certain new and useful 5 Improvements in Combs, of which the following is a specification.

This invention relates to improvements in combs; and the object of my invention is to provide a new and improved comb which is 10 simple in construction, strong, durable, and not expensive in manufacture.

In the accompanying drawings, in which like letters of reference indicate like parts in all the figures, Figure 1 is a plan view of part 15 of the female die for making the comb. Fig. 2 is a vertical transverse sectional view of the same, also showing the male die. Figs. 3, 4, 5, 6, and 7 are vertical transverse sectional views of various types and kinds of combs 20 made according to my improvement. Fig. 8 is a side view of a parting-comb, also made according to my improvement. Fig. 9 is a cross-section of a further modification.

My improved comb is to be made of hard 25 rubber, and the comb may have coarse or fine teeth, or both coarse and fine teeth, and the teeth and back may be of any desired shape.

For making the comb I use a female die A, in which are formed two molds B for two longitudinal comb-halves—that is to say, for two 30 longitudinal comb-halves—that is to say, for two half-sections like those formed by splitting a comb vertically and longitudinally. The points of the tooth-recesses in said molds are perfectly opposite each other and in line, and 35 the points of these tooth-recesses are as close to each other as possible and may even be connected. By pressing plastic or semiplastic unvulcanized rubber and finishing the upper surfaces of the material in said molds, 40 so that they are perfectly flat and smooth, two longitudinal comb-halves are formed. These two comb-halves, molded of unvulcanized rubber, are then folded together or placed against each other with their inner 45 smooth surfaces in contact, and the two halves are then united by the vulcanizing process.

It is very desirable to have the area of the comb-back increased in cross-section, especially for combing long and heavy hair, as it 50 enables one to obtain a firmer grip on the

comb, and it is less tiring to hold a comb with an enlarged back than to hold a comb with a narrow back. By enlarging the back very much material is wasted in the back and the 55 comb is made unduly heavy, and, furthermore, the sudden decrease of material from the enlarged back to the comb-teeth causes the teeth to break off much more readily from such an enlarged back than from an ordinary 60 back, as experience has shown. In order to overcome this difficulty and to make the back lighter and at the same time stronger than the solid back, I make it hollow by providing a recess or longitudinal bore within the 65 back. For this purpose male dies D are used, which are provided with a protuberance E, which when pressed upon the material in the female die produces a recess a in the inner surface of each comb-half, along the back, so 70 that when the two halves are united a longitudinal bore is formed in the back. As shown at b in Fig. 3, this bore is extended downward toward the upper ends of the teeth. As shown in Fig. 9, the recesses may extend from the 75 bore down into the teeth. As shown at b' in Fig. 4, the bore may be made circular in cross-section. As shown at b² in Fig. 7, it may be oval. This bore may also be extended into the handle H of the comb J, as shown 80 at b³ in Fig. 8. As shown in Fig. 6, a strip F of metal or other substance may be introduced between the two comb-halves along the back and may project from the top of the back. This piece F also stiffens and strengthens 85 the comb-back. As shown in Fig. 7, the bore formed in the back of the comb may be filled by means of the filling-piece G, of metal or other substance, and this also tends to strengthen and stiffen the back. As shown 90 in Fig. 9, the two shanks forming a comb-tooth d may be separated at their upper parts and held apart by a brace e.

Having described my invention, what I claim as new, and desire to secure by Letters 95 Patent, is—

1. A hard-rubber comb composed of two longitudinal comb-halves having teeth and of substantially the same size and shape, each half having a longitudinal groove formed in 100 the inner surface of its back-section, the inner surfaces of said halves being in contact,

and the two halves permanently secured to each other by the vulcanizing process to form an entirety, substantially as set forth.

2. A hard-rubber comb composed of two longitudinal comb-halves having teeth and of substantially the same size and shape, each half being provided on its inner surface with a longitudinal recess and with recesses extending from said longitudinal recess into the upper end parts of the teeth, the inner surfaces of said halves being in contact and the two longitudinal halves being vulcanized to-

gether to form, as an entirety a comb having a hollow back, and recesses extending from the hollow back into the teeth, substantially as set forth.

In testimony whereof I have signed my name to this specification, in the presence of two subscribing witnesses, this 11th day of August, 1902.

HEINRICH TRAUN.
